CLAIM

The ornamental design for a tire storage dolly, as shown and described.

DESCRIPTION

FIG. 1 is a front perspective view of a tire storage dolly, according to a first embodiment of the present design.

FIG. 2 is a rear perspective view of the tire storage dolly of FIG. 1.

FIG. 3 is a front elevation view of the tire storage dolly of FIG. 1.

FIG. 4 is a right-side elevation view of the tire storage dolly of FIG. 1.

FIG. 5 is a left-side elevation view of the tire storage dolly of FIG. 1.

FIG. 6 is a top plan view of the tire storage dolly of FIG. 1.

FIG. 7 is a bottom plan view of the tire storage dolly of FIG. 1.

FIG. 8 is a front perspective view of a tire storage dolly, according to a second embodiment of the present design.

FIG. 9 is a rear perspective view of the tire storage dolly of FIG. 8.

FIG. 10 is a front elevation view of the tire storage dolly of FIG. 8.

(Continued)

FIG. 11 is a right-side elevation view of the tire storage dolly of FIG. 8.

FIG. 12 is a left-side elevation view of the tire storage dolly of FIG. 8.

FIG. 13 is a top plan view of the tire storage dolly of FIG. 8.

FIG. 14 is a bottom plan view of the tire storage dolly of FIG. 8.

FIG. 15 is a front perspective view of a tire storage dolly, according to a third embodiment of the present design.

FIG. 16 is a rear perspective view of the tire storage dolly of FIG. 15.

FIG. 17 is a front elevation view of the tire storage dolly of FIG. 15.

FIG. 18 is a right-side elevation view of the tire storage dolly of FIG. 15.

FIG. 19 is a left-side elevation view of the tire storage dolly of FIG. 15.

FIG. 20 is a top plan view of the tire storage dolly of FIG. 15.

FIG. 21 is a bottom plan view of the tire storage dolly of FIG. 15.

FIG. 22 is a front perspective view of a tire storage dolly, according to a fourth embodiment of the present design.

FIG. 23 is a rear perspective view of the tire storage dolly of FIG. 22.

FIG. 24 is a front elevation view of the tire storage dolly of FIG. 22.

FIG. 25 is a right-side elevation view of the tire storage dolly of FIG. 22.

FIG. 26 is a left-side elevation view of the tire storage dolly of FIG. 22.

FIG. 27 is a top plan view of the tire storage dolly of FIG. 22; and,

FIG. 28 is a bottom plan view of the tire storage dolly of FIG. 22.

Where present, the broken lines shown in the figures depict portions of the tire storage dolly that form no part of the claimed design.
